FIG. 2

FIG. 1

FIG. 3

FIGURE 1 is a top plan view of a game board showing my new design.

FIGURE 2 is a side elevational view thereof taken at right angles to the view of FIGURE 1 along either side.

FIGURE 3 is a sectional view thereof taken along the lines 3—3 of FIGURE 1.

The dominant features of the design reside in the portion shown in full lines.

The characteristic features of my design reside in the combination on the game board of a substantially elliptical wall defining the playing area that is interrupted at each corner to form trapezoidal-like openings, and the particular symbols arranged on said playing area, all as shown.

I claim:

The ornamental design for a game board, as shown and described.
